UNITED STATES PATENT OFFICE.

JOSEPH GARCIA, OF PATERSON, NEW JERSEY.

TRUSS-PAD.

SPECIFICATION forming part of Letters Patent No. 449,473, dated March 31, 1891.

Application filed October 31, 1890. Serial No. 369,944. (No model.)

To all whom it may concern:

Be it known that I, JOSEPH GARCIA, of Paterson, in the county of Passaic and State of New Jersey, have invented a new and Improved Truss-Pad, of which the following is a full, clear, and exact description.

My invention relates to an improvement in truss-pads, and has for its object to provide a means whereby the pad may be conveniently and expeditiously filled with a liquid or with air as often as desired, and wherein also the interior of the pad may be effectually and thoroughly cleaned when necessary, thus preserving the rubber bag or sack constituting the inner face of the pad from the rapid decay which takes place in pads as at present constructed owing to the lack of provision made to gain access to the interior.

The invention consists in the novel construction and combination of the several parts, as will be hereinafter fully set forth, and pointed out in the claims.

Reference is to be had to the accompanying drawings, forming a part of this specification, in which similar figures of reference indicate corresponding parts in all the views.

Figure 1 is a vertical section through the pad, illustrating the attachments thereto adapted for cleaning and filling the same. Fig. 2 is a plan view of the pad ready for use; and Fig. 3 is a central vertical section through the pad when in condition to be worn and showing a modification in the attaching means.

The pad consists of a plate 10, which constitutes the outer face, and a bag or sack 11, of flexible material, such as rubber, which constitutes the inner face. The rubber sack is attached to the back of the plate 10 in any suitable or approved manner, the joint being a water tight one.

In the drawings the joint is represented as effected through the medium of a flange 12, formed upon the inner face of the plate 10 near the margin thereof and extending around the said plate, the outer face of which flange is corrugated, fluted, or otherwise roughened. The outer edges of the sack or bag 11 are cemented to the roughened outer face of the flange, and as an additional security the edges of the sack are bound to the flange by means of wire or silk threads 13. At one side of the

center of the plate 10 an opening is made, which is surrounded by an inwardly-extending sleeve 14, the bottom of which sleeve is closed except at its central portion where an aperture 15 is produced. The sleeve 14 forms, essentially, a well, in the bottom of which a washer or gasket 16 is laid apertured to correspond to the bottom of the sleeve. The upper inner surface of the sleeve is threaded to receive a hollow valve-plug 17. The plug is exteriorly threaded at its upper end, and at its lower end, which is closed, it is of less diameter than at its upper or threaded portion. The shape of the interior of the plug is rectangular or polygonal, and in the sides thereof in its lower or reduced portion one or more apertures 18 are produced. The bottom of the plug, when it is screwed as far inward as possible, rests upon the washer or gasket 16 and closes the aperture in the bottom of the well. The valve-plug is manipulated by means of a hollow key 19, which is introduced therein, as shown in Fig. 1, the upper end of the key having attached thereto a tube 20, connected with any approved form of pump. At the opposite side of the center of the plate 10 a threaded aperture is made normally closed by a stop-plug 21. When the plug is removed, a tube 22, of metal or other approved substance, is introduced for a purpose hereinafter described, or a thimble may be screwed into the opening and the tube screwed upon the thimble. If the pad is to be connected with a flexible strap 23—as leather, for instance—an opening is made in the center surrounded by an inwardly-extending sleeve 24, closed at its lower end and exteriorly threaded, into which sleeve and aperture a screw 25 is inserted, passed through the strap 23, as shown in Figs. 1 and 2. When, however, the pad is to be connected with a metal strap, as shown in Fig. 3, a nut 26 is swiveled in the center of the plate 10, the inner end of the nut being covered by a shell 27 to prevent the escape of liquid or air that may be contained in the sack or bag. The nut is provided with a diametrical channel 28 of sufficient width to receive the metal strap, and the nut and strap are rigidly connected by a set-screw 29 or its equivalent passed downward through the nut to an engagement with the strap.

In the operation of filling the pad the plug 21 is screwed in its aperture and the key 19 is introduced into the plug-valve, and said valve is unscrewed sufficiently to remove it 5 from its seat. The upper end of the key is then connected with the force-pump and the water is forced through the key into the valve and through the aperture of said valve, from whence it passes around the exterior of 10 the valve and downward through the opening in the washer 16 and the bottom of the sleeve 14 into the bag or sack 11. When the bag or sack has been filled, the plug-valve is screwed downward to its seat and the key is 15 removed. In order to thoroughly clean the interior of the bag or sack, the plug 21 is removed and the tube 22 is substituted. The plug-valve 17 is then opened in the manner above described, and water is forced into the 20 sack through the valve, and as the fresh water enters the sack the stagnant or stale water is forced upward and out through the tube 22.

It is evident that the device is simple in its construction, and that the sack may be readily filled with water or with air at any time desired, and that with equal facility and dispatch the interior of the sack may be emptied and cleaned.

Having thus described my invention, I 25 claim as new, and desire to secure by Letters Patent—

1. In a truss-pad, the combination, with the face-plate 10, having an integral threaded well 14 on its inner face provided with an aperture in its bottom, of a tubular valve-plug 30

adapted to screw into the well 14 flush with the outer face of the plate 10 and having a lateral opening and a closed inner end to close the opening 15, an annular space being formed between the lower portion of the plug 40 and well, and the upper end of the bore of the plug being angular to receive a turning-key, substantially as set forth.

2. In a truss, the combination, with the face-plate 10, having on its inner or lower 45 face an integral well 14, provided with an opening 15 and an apertured gasket 16, of the tubular plug 17, screwed into the well flush with the upper side of the plate 10 and having a lateral aperture 18 and a closed 50 lower end, an annular space being formed in the lower part of the well around the plug and the bore of the plug at its upper open end being squared, and the removable tubular key 19, open at both ends and squared at 55 its lower end to enter the said plug, substantially as set forth.

3. The combination, with the apertured face-plate 10 and the bag or sack secured thereto, of the nut 26, swiveled in the aperture of the face-plate and having a transverse opening 28, and a set-screw 29 intersecting the same, the shell 27 on the inner face of the plate 10 inclosing the inner end of the nut, substantially as set forth.

JOSEPH GARCIA.
